Inventor:

Charles Blair Swartz,
by John Middleton Donachy, his
Atty.

UNITED STATES PATENT OFFICE.

CHARLES BLAIR SWARTZ, OF BRADFORD, PENNSYLVANIA.

DISPLAY-CABINET.

1,241,164.

Specification of Letters Patent. Patented Sept. 25, 1917.

Application filed May 24, 1916. Serial No. 99,638.

To all whom it may concern:

Be it known that I, CHARLES BLAIR SWARTZ, a citizen of the United States, and resident of Bradford, Pennsylvania, have 5 invented certain new and useful Improvements in Display-Cabinets, of which the following is a specification.

My present invention relates to improvements in display cabinets and has among its 10 objects to provide a simple and attractive form of cabinet designed particularly for the display of articles of men's furnishings, in which a large number of articles may be kept on display, from which the selected 15 article may be readily withdrawn when a sale is effected and which cabinet will contain a storage compartment for holding a supply of articles to replace those withdrawn from the display compartments.

20 The invention includes the novel features of construction and the arrangement and combination of parts hereinafter described and particularly defined by the appended claims.

25 An embodiment of the invention is shown in the accompanying drawing, in which

Figure 1 is a side elevation, and

30 Figs. 2 and 3 are respectively top plan and bottom sectional views of the cabinet without its supporting stand.

In this drawing, I have shown the cabinet as designed and of the proper dimensions for the display of men's hose supporters in the boxes in which they are shipped 35 to the retailer, the cabinet being proportioned to simultaneously display sixteen boxes. It will be understood, however, that the invention is not limited to exhibiting any number of articles nor to displaying 40 any particular character of goods.

Referring by reference characters to the drawing, the numeral 1 designates a suitable base or pedestal upon which the cabinet proper is rotatably mounted. This comprises a receptacle 2 formed of any suitable material and preferably of sheet metal. 45 I prefer to make the cabinet of tapered form, in which event it would preferably be square at the top, the walls 2^a abutting each other, 50 as shown in Fig. 2, and the spaces formed by the divergence of the walls 2^a being filled by the corner strips 2^b, so that the case would have an octagonal appearance at the base. One of these walls 2^a is made in the form of 55 a hinged door, being hinged at the point 2^c and provided at its opposite edge with any

convenient form of fastening means (not shown). Each wall 2^a is provided with projecting vertical side walls 3 and transverse top and bottom walls 3^a and intermediate 60 partitions 3^b, the bottom wall 3^a and the intermediate partitions 3^b forming shelves, upon which the boxes containing the articles to be displayed are supported, the covers of the boxes being first removed and placed in 65 reversed position upon the bottoms of the boxes, leaving the articles within the boxes exposed to view.

To protect the articles from dust, I cover the compartments with glass, preferably using 70 a single sheet of glass to cover each four display compartments, as indicated at 4, and the glass may be conveniently held by sheet metal corner clips 4^a detachably connected to the cabinet by screws or similar 75 securing means. The compartments formed by the partitions between each wall 2^a and the glass are open at the side opposite the wall 3, so that the boxes may be readily inserted in and withdrawn from the compartments, and the dimensions of each compartment are preferably made such that the box fits snugly therein so that a minimum 80 amount of dust may gain access to the articles on display.

To enable the boxes to be more readily withdrawn from the compartments, I provide the glass with notches 4^b approximately arranged centrally of the side of each compartment to enable the finger to engage the 90 edge of the box. The central storage space 5 within the cabinet provides for the storage of a considerable number of boxes, from which said boxes may be removed as desired 95 to replace those on display.

A cabinet, as above described, provides for the display of a large number of articles, supports them in a protected manner, enables the ready removal of any one of the boxes which has been sold without disturbing 100 the others and permits the sold boxes to be readily replaced by the salesman, if desired, immediately upon the departure of the customer without the salesman's having to leave the cabinet.

Having thus described my invention what I claim is:—

1. A display cabinet having a central storage space and a plurality of display compartments carried by the walls thereof, one 110 of said walls being hinged to provide access to the storage space, said compartments hav-

ing glass covers and lateral openings to permit boxes carrying the articles to be displayed to be laterally inserted in said compartments.

5 2. A display cabinet comprising a suitable base and a cabinet rotatably mounted thereon and comprising a plurality of side walls forming a central storage space, one of said walls being hinged to afford access

to the storage space and said side walls having a side and transverse projecting members forming compartments opened at the other side and glass panes removably held over said compartments, substantially as described. 10

In testimony whereof, I affix my signature. 15

CHARLES BLAIR SWARTZ.
